UNITED STATES PATENT OFFICE.

CARL S. NORDEN, OF HAVERHILL, MASSACHUSETTS.

PROCESS AND MACHINE FOR MAKING WELTING.

1,407,294.

Specification of Letters Patent. Patented Feb. 21, 1922.

Application filed December 29, 1920. Serial No. 433,879.

To all whom it may concern:

Be it known that I, CARL S. NORDEN, a citizen of the United States, and a resident of Haverhill, county of Essex, State of Massachusetts, have invented an Improvement in Processes and Machines for Making Welt-
ing, of which the following is a specification.

In rounding soles before they are attached to the shoe, strips of leather are removed about the forepart, some of which are of a width as great or even greater than the width required for a welt. All of the strips removed from the sole are usually sold for scrap leather.

The primary purpose of this invention is to provide means whereby waste strips of leather may be utilized as far as possible for the purpose of making welting suitable for use in the manufacture of shoes.

The objects of my invention are to provide a process of making welting from waste leather strips and a machine for performing the various steps of said process in succession, so that the waste-strips may be inserted at one end of the machine and will be delivered at the opposite end in the form of finished welt strips, which are adapted to be attached by a scarf joint in the usual manner, to form a continuous welt strip of uniform width and thickness, the welting thus prepared being adapted to be readily conformed to the shoe, so that the welt attaching operation will be facilitated.

I accomplish these objects in the manner and by the means hereinafter described and illustrated in the accompanying drawings in which a preferred embodiment of the invention is shown, and in which:

Fig. 1 is a plan view of a machine embodying the invention.

Fig. 2 is a vertical longitudinal section thereof, at line 2—2 of Fig. 1.

Fig. 3 is a front end elevation thereof.

Fig. 4 is a detail plan view of the bed on which the entering end of the strip is shaped.

Figs. 5 and 6 are detail views of the finished welt.

Fig. 7 is a detail view, partly in end elevation and partly in cross section, of the front end of the machine.

Fig. 8 is a detail view, illustrating an initial step in the operation.

Fig. 9 is a detail view of one of the trimming knives.

Fig. 10 is a detail view of the splitting 55 knife feed rolls.

Fig. 11 is a detail view of the welt indenting rolls.

Fig. 12 is a detail view of the welt hammering devices.

In the course of the process of forming strips of leather of varying widths into a welt strip of uniform width and thickness, several operations are successively performed thereon. The first of these operations, is in 65 a sense, independent of the others, and consists in cutting the end portion of each strip down to the required width before it is introduced into the machine proper, for the final operation, this being necessary for reasons which will appear.

This preliminary operation is preferably performed with a suitably shaped die which is continuously operated, and, as illustrated, one of the main side frames 2 of the machine 75 has a bed 4 at one side thereof on which uprights 6 are mounted, and a shaft 8, having an eccentric thereon, is arranged to be continuously driven from a shaft 10 in the main machine. A cross head 12 is arranged to 80 slide vertically in the uprights 6 and is connected to an eccentric rod 14 mounted on the shaft 8. A die-block 16, illustrated in detail in Fig. 4, is mounted on the bed 4, and a correspondingly shaped die 18 is mounted 85 on the underside of the head 12.

The shape of the die and block is such that, when a leather strip, as z , is laid on the block and the die descends, the width of the strip for the length of the die is reduced to the 90 required width of the welt, and the end is cut off square, as indicated in Fig. 8. As thus prepared, the strip is then ready for insertion in the machine proper, which will now be described. The side frames 2 of the machine support a flat bed or table 3 which extends therebetween, and, at the front end of the table, a pair of edge-guides 20 are arranged to slide to and from each other at opposite sides of the path of the welt, and are 95 adapted to be withdrawn from this position by means of bell-crank levers 22, which are connected by rods 24 to treadles 26, so that, by depressing the treadles, the guides will be 100

withdrawn from each other against the action of springs 28. The inward movement of the guides by the springs is limited by stop screws 30, arranged in the frame in position to engage the levers 22.

A pair of knife-blocks 34, are arranged to slide in a guide-way 36 formed in a cross bar 38, mounted on brackets 40, secured to the side frames 2 and a knife 32 is mounted in each block, said knives being disposed at a short distance in the rear of the guides 20 and so arranged that their cutting edges are perpendicular to the surface of the table. Said knife-blocks are adapted to be adjusted towards and from each other by means of a right and left threaded screw 42. Said knives 32 are oppositely disposed with their back sides next each other and approximately parallel and their outwardly bevelled cutting edges so arranged relatively that the distance between them is equal to the width of welting desired. The stop screws 30 are so arranged that when they are engaged by the levers 22, the faces of the guides will be in exact alignment with said cutting edges.

A presser foot 44 is supported on a rod 46 directly between the guides 20, said rod being arranged to slide vertically in lugs 47, 48, on the cross bar 38, and being limited in its downward movement by a collar 50 thereon, which is held in engagement therewith by a spring 52, said collar being so adjusted that the surface of the foot 44 is at a distance from the surface of the table approximately equal to the average thickness of the leather.

A corrugated feed roll 54 is mounted on a shaft 56 in an opening in the bed directly in the rear of the knives 32, said shaft being journaled in spring-supported bearings 57 and being connected to the main shaft 55 through an "Oldham" coupling 59, to permit the shaft 56 to move out of alignment with the shaft 55. A press-roll 58 is mounted directly over roll 54 to rotate in a yoke 60, which is arranged to be vertically adjusted in guide ways 62 by means of a screw 64, the latter being swivelled in a cross bar 65 on the guide ways and threaded in the yoke 60. A splitting knife 66 is mounted on the bed 3, directly in the rear of the rolls 54 and 58, with its cutting edge in close proximity thereto, so that a leather strip, passed therebetween, will be engaged thereby, said knife being arranged to split sufficient leather from the under side of the strip to make it of uniform thickness. In practice the upper roll is adjusted with relation to the knife 66, according to the thickness of welting desired, the lower feed roll 54 being arranged to yield according to variations in thickness of the stock.

An indenting roll 68 is mounted on a shaft 10 beneath the bed and in parallelism with the shaft 56, an aperture being formed in the

bed for said roll, so that its upper surface is approximately tangentially disposed relatively thereto, and an idle-roll 72 is mounted to rotate in bearings 74, the latter being arranged to move vertically in slots formed in uprights 76, and springs 78 being arranged to press said bearings downward against the bottom of said slots. The indenting roll 68 is formed to provide a smooth middle portion 68^a and a series of indenting teeth 68^b at each side thereof, the edges of which extend from the surface of the middle portion divergently with relation to the axis of the roll, the depth, of the spaces between the teeth thus increasing from the middle to the ends.

With this arrangement, when a welt strip 80 is fed between said rolls, with its flesh side next the lower roll 68, and its edges equidistant from the middle of the roll, as shown in Fig. 11, equal portions of the welt will lie on the toothed portions of the roll. The surface of the roll 72 is exactly cylindrical and its downward movement is limited at such a point that the distance from the surface thereof to the middle surface 68^a is slightly less than the thickness of the welt strip, so that, when the strip is passed between the rolls, the teeth 68^b will be forced into both edge portions of the strip. In practice the tension of the springs 78 will be sufficient to cause the teeth to be forced into the welt nearly to the grain surface at its edge. As a result, indentations will be formed in the strip similar to those indicated in Figs. 5 and 6. The purpose of thus indenting the strip is to enable it to be more readily bent 100 about the toe of the shoe, while held flat.

As shown, the main shaft 55 is driven from a belt pulley, through a suitable clutch mechanism 53, and the roll 68 is driven at the same surface speed as the roll 54, from the shaft 55, 105 through suitable connecting gears 80.

In the operation of the machine, as thus far described, the leather strip, one end portion of which has been cut down to the required width, is pushed in, grain side up, between the guides 20, which may be withdrawn as much as necessary to permit such insertion, and the end portion is inserted between the knives 32, until it is engaged by the rolls 54 and 58, so that the latter may act to draw in the strip and feed it along, as shown in Fig. 8. The strip will then be drawn into engagement with the fixed knives 32, which will remove surplus stock from one or both edges, as may be necessary, 120 as indicated in Fig. 1, the chips removed being diverted to either side. The guides 20 will be moved in and out, by depressing or releasing the treadles, as may be required by the width of the strip at different points. 125 As the strip passes from between the rolls 54 and 58, if it is of a thickness greater than that desired, the knife 66 will split off

the surplus portion from the flesh side, as indicated in Fig. 2. Fixed guides 82 are mounted on the bed 3 between the rolls 54, 58 and the rolls 68, 72, so that the strip will be directed to the middle position on the roll 68, as it passes from the splitting knife. After the strip has been passed between the rolls 68, 72, and indented on its flesh side, as already described, it is conducted between fixed guides 92 on the bed, the passage-way therebetween being enclosed by a cover 84 and being of such width and height as to hold the strip in position without causing undue friction thereon. The feeding action through said passageway may be assisted by a feed wheel 86, which is mounted on a shaft 90, and is driven at the same surface speed as the roll 68, by means of a gear 87, which meshes with one of the gears 80, mounted on a shaft 88, the latter having a gear 91 on its opposite end, which meshes with an idle gear 89, the gear 89 being in mesh with a gear 93 on the shaft 90.

From this point the strip is delivered beneath a constantly operated hammer 94, which is adapted to subject the strip to a series of rapidly delivered blows, so as to hammer it flat in case it should tend to curl or twist. As shown in detail in Fig. 12, the hammer 94 has a shank 95, which is mounted to slide in a socket formed in the under side of a cross head 96, mounted to reciprocate vertically in uprights 98, by means of a shaft 100 having an eccentric 102 thereon, the latter being connected to the cross head by a connecting rod 104. The shaft 100 is constantly driven from the gear 87, through a gear 106, and a belt 108, passing about a pulley on the shaft 100, and a pulley on the shaft on which the gear 106 is mounted. A spring 110 is interposed between the end of the shank of the hammer 94 and the bottom of the socket in which the shank is located, and normally holds a stop pin 113 fixed in the shank, in engagement with the bottom of a slot 97 in the cross head.

The hammer 94 has a horizontal face and its width is such that it fits between the guide-ways 92, so that it may reciprocate freely therebetween. The length of the hammer is several times greater than its width, so that it will engage a considerable portion of the length of the welt at one time.

With this construction, as the welt strip is fed along between the guides 92, and beneath the hammer, the latter will be caused to strike the strip a rapid succession of blows of considerable force, the arrangement being such that the spring 110 will be compressed during the last part of the downward motion, so the strip will be subjected to pressure from the spring, as well as to the force of the blow. The length of the ham-

mer, and the timing thereof with relation to the feed, is such that each portion of the strip will be struck several blows, while it is passing beneath the same.

The welt strip, when delivered, is then ready for use, unless it is desired first to groove or bevel it. For the latter purpose a pair of feed rolls 114 may be provided, which feed the strip into engagement with a fixed beveling knife 116, arranged to bevel the strip on its under side, said rolls being driven by gears 118, from the gear 106.

A strip which is either indented, as indicated in Fig. 6, or which is beveled at one edge and indented at the other, as indicated in Fig. 5, may thus be produced. As the strips are to be made from waste stock, they will be of comparatively short lengths, when delivered from the machine, and those short strips will be connected together in the usual manner to form a continuous welt strip.

I claim:

1. In a machine for reducing strips of leather to a uniform width, a bed, a pair of edge-trimming knives spaced correspondingly to the desired width of the strip and disposed in upright position with relation to the bed, means for feeding the strip over the bed between the knives, a freely movable edge guide, at one side of the path of movement of the strip as it is fed, movable from a position at one side of said path to a position in which its guiding face and the edge of the adjacent knife lie in a common plane, and manually controlled means for holding the guide in yielding engagement with the strip.

2. In a machine for reducing strips of leather to a uniform width, a bed, a pair of edge-trimming knives spaced correspondingly to the desired width of the strip and disposed in upright position with relation to the bed, means for feeding the strip over the bed between the knives, a freely movable edge guide, at one side of the path of movement of the strip as it is fed, movable from a position at one side of said path to a position in which its guiding face and the edge of the adjacent knife lie in a common plane, yieldingly actuated means for holding the guide in engagement with the edge of the strip and manually operated means for withdrawing the guide against the action of said yieldingly actuated means.

3. In a machine for reducing strips of leather to a uniform width, a bed, a pair of edge-trimming knives spaced correspondingly to the desired width of the strip and disposed in upright position with relation to the bed, means for feeding the strip over the bed between said knives, a pair of edge guides arranged one at each side of the path of movement of the strip and in proximity

to the edges of the knives, means to hold one of said guides in a position in which its guiding surface and the edge of the corresponding knife lie in a common plane, 5 and manually controlled, yieldingly actuated means for holding the other guide in engagement with a strip as it is fed and for varying the position thereof according to the variations in width of the strip.

10 4. In a welt strip making machine, a bed, means for feeding strips of leather over said bed, means for trimming the strips to a uniform width as they are fed by said feeding means, a pair of guides between which the 15 trimmed strip is fed by said feeding means, said guides having vertical parallel guiding faces spaced to correspond to the width of the strip, an elongated hammer having a face corresponding in width to the width 20 of the strip, and means for reciprocating said hammer to strike the strip a rapid succession of blows, as it is fed between said guides.

5. A machine for trimming leather strips 25 to a uniform width and thickness, comprising a bed, a pair of edge trimming knives spaced correspondingly to the desired width of the strip and disposed in upright position with relation to the bed, a pair of feed 30 rolls disposed in the rear of said knives and arranged to draw the strip between said knives while resting on the bed, one of said rolls being held in fixed relation to the bed, and a splitting knife held in fixed relation 35 to said fixed roll at the opposite side of said rolls from said knives and adapted to split the strip to a uniform thickness as it is delivered by said rolls.

6. In a welt-strip making machine, a horizontal bed, a pair of vertically disposed 40 knives spaced to correspond to the width of the finished strip, means to draw the strip between said knives, to remove surplus material from either edge portion thereof, a 45 pair of edge-guides respectively movable towards and from the path of movement of the strip, a stop arranged to limit the inward movement of each guide with relation to the knife corresponding thereto, means 50 constantly actuated to move each guide into engagement with its stop, and means adapted to be manually operated, for withdrawing each guide from its stop.

7. In a welt-strip making machine, a hori-

zontal bed having a pair of parallel guides 55 spaced to correspond to the width of a welt-strip, a pair of knives arranged to remove opposite edge portions of a leather strip, feeding means for drawing the strip between said knives and delivering it to said guides, 60 a hammer having a horizontally disposed face, and means to reciprocate said hammer vertically, between said guides, to strike the strip a succession of blows as it is fed beneath.

8. In a welt-strip making machine, a horizontal bed having a pair of parallel guides spaced to correspond to the width of a welt-strip, a pair of knives arranged to remove opposite edge portions of a leather strip, 70 feeding means for drawing the strip between said knives and delivering it to said guides, an elongated hammer corresponding in width to the distance between said guides and means to vertically reciprocate said hammer 75 between said guides, to strike each portion of the strip a succession of blows as it is fed therebeneath.

9. In a welt-strip making machine, a pair of knives arranged to remove opposite edge 80 portions of the strip, means to feed the strip between said knives, a press roll and an indenting roll arranged in operative relation, to receive the strip from said feeding means, said indenting roll having indenting teeth 85 arranged to extend convergently from the ends thereof towards its middle portion, in position to indent the edge portions of the strip.

10. The process of making welt strips 90 which consists in trimming waste strips of leather to the required width, splitting surplus leather from the flesh side of the strip, transversely indenting the opposite edge 95 portions of the strip on its flesh side, and thereafter subjecting the strip to a succession of blows on its grain side.

11. The process of making welt strips which consists in trimming waste strips of 100 leather to a uniform width, and thickness then feeding the strip while confined between two upright parallel surfaces supported on a bed and striking the strip a rapid succession of blows on its upper side while thus held and as it is fed.

In testimony whereof, I have signed my name to this specification.

CARL S. NORDEN.
